UNITED STATES PATENT OFFICE.

AMOS MITCHELL, OF KIRKSVILLE, MISSOURI, ASSIGNOR OF ONE-FOURTH TO THOMAS B. KENNEDY AND ONE-FOURTH TO JAMES H. MUNDEN, OF KIRKSVILLE, MISSOURI.

PUMP.

1,266,974.

Specification of Letters Patent. Patented May 21, 1918.

Application filed November 8, 1915, Serial No. 60,327. Renewed February 21, 1918. Serial No. 218,593.

To all whom it may concern:

Be it known that I, AMOS MITCHELL, a citizen of the United States, residing at Kirksville, in the county of Adair and State 5 of Missouri, have invented certain new and useful Improvements in Pumps, of which the following is a specification.

The invention has relation to pumps for elevating water and which are adapted to be 10 actuated by means of weight, such as exerted by man or beast when stepping upon a platform or like movable part.

The primary purpose of the invention is the provision of a pump for supplying water 15 to a stock trough, such pump being adapted to be actuated by the weight of the animal when approaching the trough to quench its thirst.

The invention has for its object to prevent 20 the standing of water in the trough which is objectionable in cold weather since it is liable to freeze and which in warm weather becomes heated and is liable to collect dust or other foreign matter.

25 The invention contemplates a drain which is automatically actuated by the same means devised for operating the pump, said drain closing when the water is discharging into the trough and opening when the pump operating means is released from the actuating weight.

With these and other objects in view, which will readily appear as the nature of the invention is better understood, the same 35 consists in the improved construction and novel arrangement and combination of parts which will be hereinafter fully described and particularly claimed.

In the accompanying drawings has been 40 illustrated a simple and preferred form of the invention, it being, however, understood that no limitation is necessarily made to the precise structural details therein exhibited, but that changes, alterations and modifications within the scope of the invention as 45 claimed may be resorted to when desired.

Referring to the drawings,—

Figure 1 is a perspective view, parts being broken away, of a cattle or weight operated 50 pump embodying the invention;

Fig. 2 is an enlarged sectional view of the pump proper;

Fig. 3 is a side view of the pump operating means showing the trough and drain in section;

Fig. 4 is a detail perspective view of the parts illustrated in Fig. 3;

Fig. 5 is a horizontal section on the line 5—5 of Fig. 2;

Fig. 6 is a side view of a modified form of 60 pump actuating means.

Corresponding and like parts are referred to in the following description and indicated in all the views of the drawings by the same reference characters.

The numeral 1 designates a well or like source of water supply to which a pump embodying the invention is applied. The pump comprises a cylinder 2 and a piston 3, the latter being relatively fixed and the cylinder 2 mounted to have a vertical reciprocating movement imparted thereto. The piston 3 is attached to the lower end of a discharge pipe 4 which is relatively fixed and has its upper end curved to form a spout for 75 delivering the water into a trough 5. The piston 3 is hollow and is provided at its outer edge with a suitable packing to insure the formation of a water-tight joint between the piston and cylinder. The space 6 formed 80 within the piston 3 is of conical form, the flare being downward so as to cause the water to readily enter and pass through the piston upon the upstroke of the cylinder. A suitable check valve 7 is disposed in the 85 length of the discharge pipe to support the column of water therein and prevent return of the water from the discharge pipe into the well.

The cylinder 2 is provided with end pieces 90 8 and 9 which are retained in place thereon by means of rods 10, such rods passing through apertured ears forming a part of the end pieces 8 and 9. Nuts 11 threaded upon the rods 10 clamp the end pieces 8 and 9 95 against the extremities of the cylinder 2. The rods 10 are extended at their upper ends and are connected to a cross piece 12 which is slidably mounted upon the discharge pipe 4. A pair of nuts 13 threaded upon the up- 100

per end of each of the rods 10 confines the cross piece 12. Other rods 14 are connected at their lower ends to the cross piece 12 and extend upwardly along opposite sides of the discharge pipe and are yieldably connected at their upper ends to the power actuated member which preferably consists of a platform 15. The platform 15 is pivotally supported between its ends and is disposed in such relation that an animal approaching the trough is compelled to step thereon, thereby actuating the pump and causing a quantity of water to discharge into the trough 5. To prevent injury to the pump 15 and connections by a too sudden movement of the platform 15, cushioning means 16 are interposed between the platform 15 and the rods 14. Such cushioning means consist of expansible helical springs, which are mounted upon the upper ends of the rods 14 and are confined thereon between the platform 15 and suitable stops, such as pins 17 passed through openings in the upper ends of the rods 14. The rods 14 pass through openings formed in the platform 15 and extend above such platform a distance to receive the springs 16. The provision of the two rods 14 equalizes the strain and prevents binding of the movable parts. The lower end piece 9 is provided with a flap valve 18 which opens upwardly and closes downwardly, thereby confining the water in the cylinder. A screen 19 is disposed below the end piece 9 to prevent gravel or other foreign matter from entering the cylinder when the pump is in operation. The screen 19 is attached to the lower ends of the rods 10.

Under normal conditions the lower end of the cylinder 2 is some distance below the piston 3 and the pump is so placed as to be nearly or quite submerged in the water to be elevated so that upon the descent of the cylinder to a normal position the water will pass from the well or other source of supply into the cylinder through the valve 18.

When the cylinder 2 is raised by a weight being applied to the platform 15 the valve 18 becomes seated and the water confined in the lower portion of the cylinder is forced upwardly into the discharge pipe 4 and by the check valve 7 which opens as the cylinder rises. When the cylinder lowers the valve 7 closes and supports the column of water in the discharge pipe above such valve. The weight of the cylinder and connections is such as to cause the cylinder to descend when relieved of the weight applied to the platform 15 for actuating the pump.

To prevent water standing in the trough 5 a drain pipe 20 is fitted to the bottom of the trough 5 and extends above such bottom a suitable distance. An opening 21 is formed in a side of the drain pipe 20 near the bottom of the trough for the escape of the wa-

ter from the trough back into the well 65 through a cut-off pipe 22. The cut-off pipe 22 is slidably mounted in the pipe 20 and is formed in a side with an opening 23 which is adapted to register with the opening 21. The cut-off 22 has connection with the pump 70 actuating means to be operated thereby so as to throw the openings 23 and 21 out of register when the pump is operating. Any suitable means may be employed for connecting the cut-off 22 with the pump actuating means and as shown a lever 24 is pivotally connected at one end to the discharge pipe 4 and its opposite end is connected to the upper end of the cut-off 22. A rod 25 connects the lever 24 with the platform 15. 75 The several connections are adjustable to provide for proper installation and to allow for variations when placing the pump in position. Should it be required to permit the water to stand in the trough 5 the cut-off 22 may be disconnected from the actuating means and moved to a position to throw the opening 23 out of register with the opening 21. The upper end of the cut-off 22 being open provides an overflow for 80 the water and thereby prevents the overflowing of the trough upon the surface. The cut-off 22 may be adjusted so as to provide overflow for regulating the height of the water in the trough when the cut-off is disconnected from the pump actuating means. 85

In the modification illustrated in Fig. 6, the platform 15^a is pivotally supported at one end and its opposite end is connected by means of a rod 26 with a member 27 mounted upon a bracket 28, the opposite part of the member 27 being connected to the rod 14 in substantially the same manner as hereinbefore described in connection with the platform 15. The provision of the platform 15^a gives greater clearance to prevent snow, ice and foreign matter from accumulating beneath the platform and interfering with its effective operation. 90

Having thus described the invention, what is claimed as new is:—

1. A pump comprising a fixed discharge pipe, a piston at the lower end of the discharge pipe, a cylinder slidable upon the discharge pipe and piston, end-pieces fitted to the extremities of the cylinder, the lower end piece having an opening which is controlled by means of an upwardly opening valve, rods connecting the end pieces and having their upper ends extended, a cross piece connecting the extended ends of the rods, and other rods connected to the cross piece and transmitting movement to the cylinder. 105

2. In a pump an operating member 125 mounted for reciprocation, a platform mounted for tilting movement and operatively connected to the operating member,

a swingingly mounted lever arm, a link connecting one end portion of the platform with an intermediate portion of the lever, a liquid receiving receptacle, a drain pipe 5 opening through the bottom of the receptacle and provided near the bottom with an opening in its side, a pipe telescopically fitting in the drain pipe and provided with an opening adapted in one position to register with the opening in the drain pipe, and 10 operative connection between the second pipe and the lever.

In testimony whereof, I affix my signature.

AMOS MITCHELL. [L. s.]
